ATTORNEY

UNITED STATES PATENT OFFICE.

CHARLES F. BLOCH, OF ROCKY FORD, COLORADO.

WRENCH.

1,260,505.

Specification of Letters Patent. Patented Mar. 26, 1918.

Application filed November 26, 1917. Serial No. 204,015.

To all whom it may concern:

Be it known that I, CHARLES F. BLOCH, a citizen of the United States, residing at Rocky Ford, in the county of Otero and 5 State of Colorado, have invented certain new and useful Improvements in Wrenches, of which the following is a specification.

This invention relates to wrenches, and more particularly to that type of wrenches 10 employing a fixed jaw and a slidable jaw movable toward and away from the fixed jaw.

One of the main objects of the invention is to provide a wrench of the character 15 stated of simple construction and operation which can be produced at very small cost, and which is provided with simple and efficient means for adjusting the movable jaw. Another object is to provide a wrench which 20 is of smooth contour and compact construction so as to be readily carried in a tool kit. A further object is to provide a wrench in which the shanks of the gripping jaws telescope, and the adjusting means for the movable jaw is positioned within the shank of 25 this jaw, simple and efficient means being provided for operating this adjusting device and for locking it in adjusted position. Further objects will appear from the detailed description.

Figure 1 is a side view of a wrench constructed in accordance with my invention the shanks of the jaws being longitudinally sectioned to show the adjusting means.

35 Fig. 2 is a top plan view.

Fig. 3 is an end view.

Fig. 4 is a section on line 4—4 of Fig. 1.

Fig. 5 is a section on line 5—5 of Fig. 1. The movable jaw 1 of the wrench is provided with an integral shank 2 disposed substantially at right angles thereto which is slidably mounted in the shank 3 of jaw 4, this shank 3 being of polygonal cross section and provided with a bore 5 adapted to 40 snugly receive shank 2, the shanks of the two jaws being thus telescopically connected. Shank 2 of fixed jaw 1 is provided with an axial bore 6 extending from the outer end thereof, and is internally threaded to receive an adjusting screw 7 which is passed through an aperture in the outer end 3a of shank 3. A pin 8 is secured through screw 7 diametrically thereof and projects beyond each side of the screw, this pin being closely 45 adjacent the inner face of end 3a of shank 3 so as to prevent outward longitudinal movement of the adjusting screw while permitting free rotation of this member in either direction. A collar 9 is secured on screw 7, by being threaded thereon or any other 50 suitable manner, closely adjacent the outer face of the outer end of shank 3. This collar and pin 8 coöperate to provide a connection between shank 3 and adjusting screw 7 which permits free rotation of the screw in either direction while effectually preventing 55 axial movement of the screw relative to the shank.

From the above described construction it will be evident that, by rotating adjusting screw 7 in the desired direction, movable jaw 1 may be moved toward or away from fixed jaw 4 so as to be adjusted to tightly grip an article about which the wrench jaws 1 and 4 are placed in the usual manner. 60 The outer end of screw 7 is bifurcated to provide the spaced ears 10. An operating lever 11 is pivotally secured at its lower end between these ears by a pivot pin 12 inserted through an eye 13 provided at the 65 lower end of end arm 14 of this lever. Arm 14 is disposed substantially at right angles to the larger operating arm 15 of the lever. This arm 15 is of substantially rectangular cross section, its undersurface being flat or 70 plane, and the arms 14 and 15 of the levers are so related that, when the lever is turned about pivot pin 12 so as to bring arm 15 into parallelism with the upper surface of shank 3, the under face of this arm will 75 fit snugly against the upper face of the shank. The arms 14 and 15 of the operating lever thus coöperate, when the lever is in depressed position, to securely lock the adjusting screw 7 against rotation, thus securing 80 the movable jaw 1 in adjustment relative to fixed jaw 4. When it is desired to rotate the adjusting screw, lever 11 may be turned outward and upward about pivot pin 12 so as to bring the arm 15 into a substantially 85 vertical position, this arm thus providing a lever by means of which the adjusting screw 7 may be quickly and easily rotated in either direction desired so as to adjust jaw 1, after 90 which the lever may be turned down so as 95 to lock the jaw in adjustment. This operation will be clear from Fig. 1 of the drawings in which the position of lever 11 when used for rotating screw 7 is indicated. When the lever 11 is in depressed position 100 105 110

it, fits snugly against the upper face of shank 3 and occupies but very little space, thus avoiding all interference with the use of the wrench in the usual manner.

5 While I have shown the adjusting lever 11 so shaped and proportioned as to fit snugly against the upper face of shank 3, it will be evident that any equivalent means for holding this lever against movement when 10 depressed so as to prevent rotation of the adjusting screw can be employed, the main object being to provide a locking device of simple and efficient construction which will not interfere with the use of the wrench in 15 the ordinary manner and will permit the adjusting screw to be quickly and easily rotated when desired, this means also serving to facilitate rotation of the screw. It will be evident that there may be slight changes 20 made in the construction and arrangement of the different parts of my invention without departing from the field and scope of the same, and I intend to include all such variations, as fall within the scope of the 25 appended claim in this application in which a preferred form only of my invention is disclosed.

What I claim is:

In a wrench, a fixed jaw having a tubular shank, a movable jaw having a shank 30 slideable in the shank of said fixed jaw, said shank of the movable jaw being axially bored and threaded from its outer end, an adjusting screw threaded into the bore of the shank of the movable jaw, said adjusting 35 screw being mounted in the outer end of the shank of the fixed jaw for free rotation and secured against axial movement relative to said shank, the shank of said fixed jaw being of polygonal cross section, and an ap- 40 proximately rectangular or L-shaped operating lever having its vertical arm pivotally secured at the lower end thereof to the outer end of said screw and its horizontal arm so disposed relative to the vertical arm as to 45 engage one face of the shank of said fixed jaw when the lever is in operative position so as to lock said screw against rotation.

In testimony whereof I affix my signature in presence of two witnesses.

CHARLES F. BLOCH.
